WALTER WRIGHT, OF SAN FRANCISCO, CALIFORNIA, ASSIGNOR, BY MESNE ASSIGNMENTS, TO UNDERWOOD COMPUTING MACHINE COMPANY, A CORPORATION OF NEW YORK.

COMPUTING MECHANISM.

1,185,566.

Specification of Letters Patent.

Patented May 30, 1916.

Application filed November 13, 1908, Serial No. 462,498. Renewed August 3, 1911. Serial No. 642,042.

To all whom it may concern:

Be it known that I, WALTER WRIGHT, a citizen of the United States, residing at San Francisco and State of California, have invented new and useful Improvements in Computing Mechanism, of which the following is a specification.

The present invention relates to computing mechanism.

10 The object of the invention is to provide a series of computing wheels, which are always in positive engagement with their respective carrying wheels, and which can be rotated in either direction and thus perform either addition or subtraction.

15 A further object is to provide a continuous series of such mechanisms in operative connection with each other, said series to contain any reasonable number of computing wheels, the construction being such that the number need not be limited.

20 A further object is to provide mechanism whereby when any wheel of the series may be operated, all of said wheels except the one 25 in operative engagement with the operating means, are positively locked against possible rotation, except when carrying from one wheel to the next; and whereby any computing wheel, while in operative engagement 30 with the operating means, is free to rotate therewith, and through such rotation it becomes the master or operating wheel, through which the next computing wheel to the left, or any number of such computing 35 wheels at that time in the operating zone, may be actuated when it is necessary to carry or transfer from one wheel to the next in the performance of addition or subtraction.

40 A further object is to provide mechanism, in which the computing wheels, being at all times positively geared with their carrying mechanism, in the operating zone and locked against possible erroneous rotation, do not 45 require the disengagement of one from the other, when any one of the computing wheels is in operative engagement with the operating means, thus avoiding the necessity of unmeshing the carrying means, from 50 the computing wheels, when same is being actuated by the operating means; thereby providing a novel construction, in which all levers, springs and safety devices heretofore

used to accomplish this result, are dispensed with and made unnecessary.

55 A further object is to provide a mechanism of this character which may be used in connection with operating means laterally stationary, and the computing mechanism movable, or the computing mechanism 60 fixed against lateral movement, the operating means being laterally movable, and whereby the lateral movement of either the computing mechanism or the operating means, enables the computing wheel in operative engagement with the operating means 65 to rotate freely therewith, and at the same time through such rotation freely rotate through one-tenth of a revolution any desired number of computing wheels of the 70 series in the operating zone then on the left, whenever it is necessary to carry from one wheel to the next, either in the performance of addition or subtraction.

75 As shown the present mechanism is actuated by means carried on a rotary driving shaft, over which the number wheels move in a step by step movement, the spacing means being equal to the width of a number wheel, or the computing wheels may be stationary and the operating means move 80 through the computing wheels. However, the invention is not limited to internal actuating means, as the computing wheels can just as readily be rotated by external or outside operating means.

85 In the accompanying drawing, Figure 1 is a side elevation of the computing mechanism partly shown in section, and parts being broken away; Fig. 2 is a transverse section on the line 2—2 of Fig. 1; Fig. 3 is a detail of one of the driven gear wheels.

90 For convenience, the present invention will be described as applied to a typewriting machine, but it is understood that it is not limited to this purpose.

95 The computing wheel 1, together with the gear portion 2, secured thereto on the right, is of a width corresponding to a writing space of a typewriter; and a sufficient number 100 of such wheels may be combined in a frame or carriage, to extend through a distance corresponding with the number of writing spaces to the writing line of a typewriter, there being in such case one number 105 wheel for each writing space, except in each

fourth writing space, at which points the hub 5 of the third computing wheel extends through a partition and occupies with the collar 5^a a double space, or the space of two computing wheels. At these points the driving means are rendered inoperative, the internal gear teeth, 3 hereafter referred to, on the extended hub portion 5 of the computing wheel, being cut away from that portion of such third wheel, thus permitting the operating means to revolve freely therein without affecting the rotation of the computing wheels. This also allows, when used in connection with a printing mechanism, for the printing of a period or comma in such fourth spaces, which could be used to advantage in dividing the hundreds from the thousands, thousands from millions, millions from billions, dollars from cents, etc.

Each computing wheel is composed of a main body portion 1, and a gear 2, secured to the main portion on the right, the outside diameter of the gear teeth of the wheel 2 being flush with the outside diameter of the main body of the wheel 1, upon the surface of which the nine digits and 0 are formed. The hub is also provided with ten internal gear teeth 3, thus providing a corresponding number of recesses 4 capable of being selectively engaged by lugs or pins 6 extending laterally from a raised portion 7 of a hub or collar 8 secured to a driving shaft 9. The pins 6 are preferably formed upon a raised portion 7 of the hub 8, the hub being cut away at each side of said raised portion so as to make the outside diameter the same as the internal diameter of the stationary tubes 10, each of which, at one end, rests upon said lowered portion of the hub 8, their other ends being secured against rotation by collars 11 on arms 12 supported on the frame of the machine.

The fixed or stationary tubes 10 and the raised portion of the hub 8 are both of the same diameter as the internal gear teeth of the computing wheel 1. The computing wheels are supported in a frame comprising end plates 13 and partitions 14, through which latter extend rods 15; and said wheels, in the step by step movement of the frame or carriage, slide over the fixed tubes 10.

The carrying mechanism is composed of a gear wheel 16 and a Geneva lock wheel 17, the hub portion of each being formed with five internal recesses 18 and 19. The gear wheel 16 and Geneva lock 17 are each of substantially one half the width of a computing wheel, the combined width of both the gear wheel 16 and Geneva lock 17 being of substantially the same width as a computing wheel. There is one gear wheel 16 to correspond with each computing wheel, with which it is positively geared. The means for causing the gear wheel 16 and the Geneva lock 17 to act as one when in the

operating zone, is the five toothed wheel 20, the teeth 21 of which are adapted to jointly engage the internal recesses 18 and 19 of a gear wheel 16 and a Geneva lock 17. There are a number of these wheels 20 loosely mounted on a stationary shaft 31, supported on the arm 12. The hub of the wheel 20 is of a width corresponding to that of a computing wheel, and of substantially the same width as the gear wheel 16 and the Geneva stop wheel 17 combined. The teeth 21 of the wheel 20, however are of a slightly less width, for the purpose of allowing the clearance required in the rapid operation of the computing mechanism.

As the gear 2 does not extend beyond the main body of the computing wheel to which it is secured on the right, the gear portion of the wheel 16 cannot be of greater width than the gear 2; therefore the teeth and a portion of the hub of the gear wheel 16 are cut away on the right, as shown at 22, to allow clearance for the carrying pin 23, formed on the periphery of the computing wheel 1. When any computing wheel is operated, so as to make a complete revolution, and the carrying pin 23 comes in contact with one of the five recesses 24, in the Geneva stop wheel 17, and thereby rotates said wheel 17 through one fifth of a revolution, it will through the medium of the five internal recesses 18 and 19, in which are engaged the teeth 21 of the wheel 20, also carry with it the gear wheel 16 immediately to the left, which is also in engagement with the teeth 21 of the wheel 20; and as this gear wheel 16 is also in mesh with the gear 2 of the next computing wheel to the left, the said computing wheel will also be rotated through one tenth of a revolution. Should all the computing wheels in the operating zone, in case of addition, be standing at "9," at the time the operation takes place, this action would be continued throughout the operating zone, or as far as the five point wheels 20 extend, and until the particular number wheel in mesh with the last gear wheel 16 in the operating zone was rotated. The rotation of this last gear 16 would not affect the next computing wheel to the left, even though that computing wheel should also be standing at 9, because the rotation of the Geneva stop wheel 17 corresponding to this particular number wheel would at that point have no effect upon the rotation of the next computing wheel, owing to the fact that the next gear wheel 16 is not operatively connected with the Geneva stop wheel 17 at that time by reason of there being a break 25 between the last wheel 20 and the fixed sleeve 26, which latter at this point, takes the place of the wheels 20, the teeth 27 being cut away at 25 for the purpose of limiting the carrying capacity of the mechanism, and to act 130

as a safety device for breaking the throw from one wheel to another at that particular point.

- The computing wheel in operative engagement with the operating means cannot rotate the next, or any of the computing wheels, which are at that time to the right of same, because the gear portion 16 of the carrying mechanism, which is always in positive mesh with the gear portion 2 of the computing wheel referred to, is at that time free to rotate with the computing wheel, but independently of the Geneva portion 17 of such carrying mechanism, which at all other times must rotate with the gear portion 16 of the carrying mechanism. The reason for this is, that at the point where the computing wheels are in operative engagement with the operating means, there is no five point wheel 20 on the shaft 31, the teeth 21 of which at other points in the step by step travel of the computing mechanism to the left, are in positive engagement with the internal recesses 18 and 19 in the hubs of both the gear carrying wheel 16 and the Geneva lock wheel 17 corresponding therewith to complete the carrying mechanism from that particular computing wheel to the next. There is also a cut away portion or collar 28 provided on the sleeve 29 shown at the operating point; and it is this break 28, which extends from the end of the teeth 30 on the fixed sleeve 29 to the teeth 21 of the first wheel 20, to the left which permits the computing wheel in engagement with the operating means to rotate freely, and without affecting the next or any wheels then standing to the right of same. The reason for this is that the gear wheel 16, in mesh with the gear portion 2 of the computing wheel referred to, can rotate freely therewith around the collar or hub 28 of the sleeve 29 secured to the shaft 31; but as the carrying pin 23 on the computing wheel being thus rotated, comes in contact with one of the recesses 24 of the next Geneva stop wheel 17, standing to the left of the gear wheel 16 in engagement with the computing wheel referred to, it will, through engagement with the recess 24, carry said wheel 17 through one fifth of a revolution. This Geneva lock wheel 17, will also, through the medium of the wheel 20, the teeth 21 of which are also in engagement with the five internal recesses 18, of the next gear wheel 16 to the left, cause it to rotate through one fifth of a revolution; and as the external gear teeth of this wheel 16 are always in positive engagement with the next computing wheel, it will also, at the same time be carried by this operation through one tenth of a revolution. Should the next computing wheel, or all the computing wheels in the operative zone be standing at 9, in case of addition, when the carrying pin 23 of the computing wheel in operation comes in contact with and rotates the first Geneva stop wheel 17 to the left of the collar 28 through one fifth of a revolution, then all the computing wheels to the left, that are within the operating zone, which is limited only by the number of wheels 20 carried between the breaks or collars 25 and 28, will be rotated through one tenth of a revolution, but all computing wheels which have passed beyond the five point wheels 20 will not be affected in any way, nor will the computing wheels to the right, which are yet to the right of the break 28 because the shaft 31 is non-rotatable and the teeth are carried on the sleeves to the right as well as to the left of the idlers 20 and the breaks 28 and 25 on the sleeves.
- When a computing wheel to the right of a partition 14 is operated, the carrying from one computing wheel to the next is carried through the partition to the first wheel on the opposite side thereof, in the following manner. The Geneva stop wheel 17 to the right of the partition 14, has on its left an extended hub portion 32, which extends through a partition as shown at 33, and over which when in place is a fixed collar 34. The internal recesses 19 of the Geneva stop wheel 17, are extended through the hub portion 32, so that when the carrying pin 23 of the computing wheel to the right of the partition 14, comes in contact with a recess 24 of the Geneva stop wheel 17, it rotates through the hub extension 32 of said wheel, two of the five point wheels 20 through one fifth of a revolution, and as the second of these wheels 20, the one farthest to the left, is also in positive engagement with the next gear wheel 16, and, as this wheel is also positively geared to the next computing wheel 1 to the left, said computing wheel is actuated through one tenth of a revolution.
- It will be understood that only those tens-carrying devices which are included between the two breaks 25 and 28 can be active at any time. The sleeves 27 and 29 are always idle, and may extend through any number of tens-carrying wheels to the left of the break 25 and to the right of the break 28. The wheels engaged by said idle sleeves 27, 29 are locked by said sleeves out of use. The motion of these wheels is derived from the master wheel 7, and only those tens-carrying wheels to the left of said master wheel and to the right of the sleeve 27 can be connected to carrier tens. In other words the extent to which tens can be carried is limited to substantially less than the whole number of adding wheels in the system, although the tens-carrying mechanism is always effective, no matter which of the main adding wheels are within the sphere of action of said tens-carrying mech-

anism, said sphere of action or operating zone extending from one break 25 to the other break 28.

I claim:—

5. 1. In a computing mechanism, number wheels, operating means therefor carrying mechanism for carrying from one number wheel to the next, composed of a pinion and Geneva stop wheel, a shaft for supporting 70 same, said shaft, and said pinion and stop wheel being relatively movable, and means loosely mounted on said shaft to engage both the pinion and stop wheel, whereby they rotate as one, when actuated by the 75 10 rotation of the number wheel in operative engagement with the operating means, substantially as described.

2. In a computing mechanism including a pinion and Geneva stop wheel, comprising 80 number wheels and carrying mechanism therefor, means to operate the number wheels, a shaft, means loosely mounted thereon having a part adapted to engage the hubs of a pinion and Geneva stop wheel, 85 15 said means and the pinion and Geneva stop wheel, being axially relatively movable one to the other, and means whereby through the rotation of the Geneva stop wheel, said pinion is caused to rotate therewith through 90 one fifth of a revolution, and through such rotation, actuate the next number wheel in 95 20 mesh with said pinion, through one tenth of a revolution, substantially as described.

3. In a computing mechanism comprising 100 number wheels and carrying mechanism therefor adapted to carry from one number wheel to the next, means to operate the number wheels, a shaft for said carrying mechanism, and means loosely mounted on said 105 25 shaft whereby the rotation of said carrying mechanism, actuates the next number wheel through a distance corresponding therewith, such rotation being caused through the rotation of the number wheel actuated by the 110 30 operating means, substantially as described.

4. In a computing mechanism, number wheels, carrying mechanism therefor, composed of a pinion and a Geneva stop wheel, a stationary shaft, both said pinion and said 115 35 stop wheel being loosely mounted on said shaft, and means carried on said shaft adapted to engage both the pinion and Geneva stop wheel, whereby through the rotation of the number wheel in operative 120 40 engagement with the actuating means, the next number wheel is actuated through one tenth of a revolution, substantially as described.

5. A computing machine, combining a series 125 45 of denominational digit wheels; and denominational trains for carrying tens from one wheel to the next, each train embodying a pair of relatively-rotatable elements, and a coupler for locking the same together 130 50 to rotate in unison, said pairs of rotatable

elements and said couplers having permanently-unobstructed, relative lateral movement therebetween, so as to enable a coupler, during computation, to be disengaged from one pair of rotatable elements and directly 70 engaged with the next pair at one such relative movement.

6. A computing machine, combining a series 75 55 of denominational digit wheels; and denominational trains for carrying tens from one wheel to the next, each train embodying a pair of relatively-rotatable elements, one connected with a digit wheel of lower order, and the other with a digit wheel of higher order, and a rotatable coupler for 80 keying said elements together for rotation in unison, said pairs of rotatable elements and said couplers having permanently-unobstructed, relative lateral movement therebetween, so as to enable a coupler, during computation, to be disengaged from one pair of rotatable elements and directly engaged 85 60 with the next pair at one such relative movement.

7. The combination, with a series of denominational digit wheels; of tens-carrying mechanism therefor, embodying a series of independently-rotatable couplers, and a series of pairs of independently-rotatable carrying wheels, each of such pairs comprising a pinion and a Geneva stop wheel arranged face to face, interposed between 90 65 said couplers and said digit wheels and adapted to be locked together by the former for rotation in unison, said pairs of carrying wheels and said couplers having permanently-unobstructed, relative lateral movement therebetween, so as to enable a coupler, during computation, to be disengaged from one pair of carrying wheels 95 70 and directly engaged with the next pair at one such relative movement.

8. The combination, with a series of denominational digit wheels; of tens-carrying mechanism therefor, embodying a series of 100 pairs of independently-rotatable carrying wheels, each of such pairs comprising a pinion and a Geneva stop wheel, and a series of independently-rotatable coupler disposed internally of said pairs of carrying 105 75 wheels to lock the component members of the latter together for rotation in unison, said pairs of carrying wheels and said couplers having permanently-unobstructed, relative lateral movement therebetween, so 110 80 as to enable a coupler, during computation, to be disengaged from one pair of carrying wheels and directly engaged with the next 115 85 pair at one such relative movement.

9. A computing machine, combining a series 120 90 of denominational digit wheels; and denominational devices for carrying tens from one wheel to the next, each tens-carrying device embodying a locking wheel constantly engaging the digit wheel of lower 125 95 130

- denomination, a carrying wheel constantly engaging the digit wheel of higher denomination, said locking wheel and said carrying wheel rotatable relatively to each other, 5 and a member for keying said locking wheel and said carrying wheel together to rotate in unison, said locking and carrying wheels and said keying members having permanently-unobstructed, relative lateral movement therebetween, so as to enable a keying member, during computation, to be disengaged from the locking and carrying wheels of one tens-carrying device and directly engaged with those of the next 10 vice at one such relative movement.
10. The combination, with a master wheel, and a gang of computing wheels; of Geneva movements for carrying tens from wheel to wheel along the gang, each 20 Geneva movement comprising a pair of co-operating members disconnected from each other; and a series of devices associated with the co-operating members of said Geneva movements for connecting the same, a part 25 of the series of connecting devices acting to couple together for rotation the co-operating members of the Geneva movements below the master wheel, the first-named part at and above the master wheel, and the remaining part acting to lock against rotation 30 the co-operative members of the Geneva movements below the master wheel, the first-named part of the series of connecting devices being spaced from the second-named part to disrupt 35 connection between the Geneva movement at the master wheel and that next below.
11. The combination, with a master wheel, and a gang of computing wheels; 40 of Geneva movements for carrying tens from wheel to wheel along the gang, each Geneva movement comprising a pair of co-operating members disconnected from each other; a set of independently-revoluble elements 45 associated with the co-operating members of the Geneva movements at and above the master wheel, to couple the same together for rotation; and a single stationary element for engaging the co-operating members of all 50 the Geneva movements below the master wheel to prevent rotation thereof.
12. The combination, with a master wheel, and a gang of computing wheels; 55 of Geneva movements for carrying tens from wheel to wheel along the gang, each Geneva movement comprising a pair of co-operating members disconnected from each other; means for connecting together for rotation the co-operating members of the 60 Geneva movements at and above the master wheel; and means distinct from the last-named means for connecting together, as a lock against rotation, the co-operating members of the Geneva movements below the 65 master wheel, the first- and second-named
- connecting means and the said Geneva movements having permanently-unobstructed, relative lateral movement therebetween, so as to enable said first- and second-named connecting means, during computation, to 70 directly engage the co-operating members of the successive Geneva movements at successive relative movements.
13. The combination, with a master wheel, and a gang of computing wheels; of 75 Geneva movements for carrying tens from wheel to wheel along the gang, each Geneva movement comprising a pair of co-operating members disconnected from each other; a set of independently-revoluble elements associated with the co-operating members of the Geneva movements at and above the master wheel, to couple the same together for rotation; and a single stationary element for engaging the co-operating members of all 80 the Geneva movements below the master wheel to prevent rotation thereof, the said Geneva movements and the said coupling elements and locking element having permanently - unobstructed, relative lateral 85 movement therebetween, so as to enable, at one such relative movement during computation, the coupling elements to be disengaged from the Geneva movements with which they were engaged and directly engage with the next higher Geneva movements, and the locking element to be directly engaged with the next higher Geneva 90 movement.
14. The combination, with a gang of computing wheels; of devices for carrying tens along said gang, each tens-carrying device comprising members free of connection to each other; a series of independently-movable connectors for connecting together the 100 members of the tens-carrying devices in succession, said tens-carrying devices and said series of connectors having permanently unobstructed, relative lateral traveling movement therebetween; and means at 105 each end of said series of connectors for engaging the members of the tens-carrying devices opposite the same, to hold them against rotation, each of said holding means and the adjacent end of the series of connectors having a gap intervening therebetween.
15. In a computing machine, the combination with a series of computing wheels, of a casing for said wheels, partitions in 110 said casing at each fourth unit space, a carry over wheel for each computing wheel, an elongated hub on each carry over wheel that extends past the adjacent partition, and a collar fast on said partition holding said 115 carry over wheel alined by its hub.
16. In a computing machine, the combination, with computing wheels; of carry-over devices each comprising a gear permanently engaging its computing wheel, and 120

an idle wheel associated with each carry-over gear, but detached therefrom; a master wheel arranged to drive said computing wheels *seriatim*; members permanently located on one side of said master wheel for coupling each idle wheel to its carry-over gear, so as to lock for operation the carry-over devices at and above the master wheel; and a fixed member permanently located on the other side of said master wheel for locking the carry-over devices below the master wheel against operation.

17. The combination, with a set of computing wheels, and a master wheel for driving the same; of a tens-carrying train extending from each computing wheel to the next higher computing wheel, each train being normally broken or interrupted, so as to be incapable of carrying between juxtaposed computing wheels; and coupling means for completing said trains *seriatim*, said coupling means and said trains having a step-by-step, relative lateral movement therebetween, which is permanently unobstructed, so that at each stop said coupling means will be disengaged from one train and directly engaged with the next.

18. A computing apparatus combining a totalizer, a master wheel, said master wheel and totalizer having relative traverse in axial direction, tens-carrying trains connecting adjacent denominations of the totalizer, said trains each comprising a pair of coaxial elements relatively rotatable, and rotatable devices to couple said elements, said coupling devices being permanently disposed to the left of said master wheel and controlled with relation to said trains by said relative traverse.

40 19. In a computing machine, the combination, with a series of computing wheels, and carry-over wheels driven thereby; of a connection between each carry-over wheel and the next higher computing wheel, comprising a gear for said computing wheel and a gear for said carry-over wheel constantly meshing with the first-named gear, said computing wheels and their gears, and said carry-over wheels and their gears constituting two companion series of coaxial elements, one of which series has its associated component elements connected to rotate in unison, the other series having its component elements free of connection and formed with alining internal teeth or notches; and toothed coupling devices disposed internally of said other series for engagement with the teeth or notches thereof, to connect together associated elements of that series for rotation in unison, but releasable therefrom to break such connection.

20. A computing apparatus combining a series of computing wheels, a master wheel arranged to operate them *seriatim*, denominational carry-over devices each comprising

two coaxial members and forming a train with said wheels either driving or locking each wheel from the one below, a gear coaxial with each computing wheel forming part of the corresponding carry-over train, two coaxial elements of each train being permanently coupled and the other two normally uncoupled, and keying means fixed relatively to the master wheel for coupling the uncoupled coaxial elements of each train above the master wheel.

21. A computing apparatus combining a series of computing wheels arranged together in a set to form a computing head, a master wheel for driving said computing wheels *seriatim*, carry-over mechanism for enabling one computing wheel to carry tens to or borrow tens from the next higher computing wheel, and coupling means internal to said carry-over mechanism for enabling the locking of said computing wheels against movement, said set of computing wheels and said coupling means having permanently unobstructed relative traveling movement, so that said computing wheels may be locked successively one by one against movement.

22. The combination, with a series of computing wheels, and a master member; of a set of tens-carrying devices comprising, each, a pair of relatively-movable members; a series of independently-movable connectors for coupling together the members of the successive tens-carrying devices at and above the master member, said computing wheels and master member, and said tens-carrying devices and connectors having relative traverse therebetween; and means disposed in advance of said series of connectors for successively engaging the relatively-movable members of tens-carrying devices opposite the same, to hold them against rotation.

23. The combination, with a series of computing wheels, and a master member; of a set of tens-carrying devices comprising, each, a pair of relatively-movable members; a series of independently-movable connectors for coupling together the members of the successive tens-carrying devices at and above the master member, said computing wheels and master member, and said tens-carrying devices and connectors having relative traverse therebetween; means disposed in advance of said series of connectors for successively engaging the relatively-movable members of tens-carrying devices opposite the same, to hold them against rotation; and means for breaking the transfer between successive tens-carrying devices engaged with the front connector and with said holding means.

24. The combination, with a series of computing wheels, and a master member; of a set of tens-carrying devices comprising,

each, a pair of relatively-movable members; a series of independently-movable connectors for coupling together the members of the successive tens-carrying devices at and above the master member, said computing wheels and master member, and said tens-carrying devices and connectors having relative traverse therebetween; and means disposed in advance of said series of connectors for successively engaging the relatively-movable members of tens-carrying devices opposite the same, to hold them against rotation, said holding means and the front connector having a gap between them, to break the transfer between successive tens-carrying devices engaged with the front connector and with said holding means.

25. The combination, with a series of computing wheels, and normally-open trains for

carrying tens from wheel to wheel; of a master wheel for driving said computing wheels; a series of independently-movable elements for closing the successive tens-carrying trains at and above the master wheel, said computing wheels and master wheel, and said tens-carrying trains and closing elements having relative traverse therebetween; and means disposed in advance of said series of closing elements for successively locking against operation the trains opposite said means.

In testimony whereof I have hereunto set my hand in the presence of two subscribing witnesses.
